FLUID OPERATED RELAY MECHANISM

Guido Wünsch, Berlin-Steglitz, Germany, assignor to Askania-Werke A. G. vormals Central Werkstatt Dessau und Carl Bamberg-Friedenau, a company of Germany

Application September 17, 1936, Serial No. 101,329
In Germany December 11, 1935

4 Claims. (Cl. 137—111)

This invention relates to fluid pressure operated relays such as are employed in regulators for controlling physical conditions and, among other objects, aims to provide important improvements in fluid jet relays such as those of the well known "Askania" type, whereby to increase the efficiency and reduce the power required to supply the pressure fluid. The main idea is to produce the most efficient ratios between the sizes of the jet nozzle and the orifice or orifices into which the jet discharges, so that both the pressure regain or effective pressure in and the volume of fluid delivered to the control conduits for actuating the servo motor or control device may be increased to a maximum for any ordinary operating fluid medium.

Other aims and advantages of the invention will appear in the specification, when considered in connection with the accompanying drawing, wherein:

20 Fig. 1 is a sectional view showing jet pipe relay mechanism embodying the invention;

Fig. 2 is a sectional view taken at right angles to Fig. 1;

25 Fig. 3 is a fragmentary sectional view of a tube and conduit to illustrate the relative sizes of the nozzle and a receiving orifice; and

30 Figs. 4 and 5 are charts illustrating the efficiency of jet pipe relay systems embodying the invention.

In relay mechanisms of the type illustrated, the pressure fluid is usually supplied by a pump and the velocity of the fluid is transformed into a pressure head which is delivered through either 35 one of two small orifices of a pair of control conduits to actuate a servo motor or control device (not shown). The pressure and volume of the fluid delivered to the control device through the conduits, in conjunction with other factors, determine the energy delivered to the control device. It is therefore highly desirable to regain a high 40 percentage of the pump pressure in and to deliver a maximum volume of the fluid to the control conduits. That is to say, both the pressure efficiency and the volumetric efficiency are very important factors. Heretofore, the sizes of the jet nozzle and the orifices have been practically the same. An appreciable percentage of pressure loss and low volumetric efficiency, with consequent 45 power waste, increase in size, capacity and cost of pumping equipment, have been tolerated. In some installations, considerable power is required to operate heavy control equipment and the losses 50 involve heavy expense. The present invention,

therefore, aims to reduce such losses and greatly increase the efficiency of such relay systems.

Referring particularly to the drawing, Figs. 1 and 2 disclose an "Askania" jet pipe relay system embodying the invention. This particular type of pivoted jet pipe is the subject of a co-pending application, Ser. No. 93,306, filed July 29, 1936. However, it is to be understood that the invention is equally applicable to all relay systems wherein fluid jets are delivered to orifices of controlling conduits. The illustrated system discloses a jet pipe 10 carried by a bar 11 having trunnion pins 12 and mounted for pivotal movement in a vertical plane. Pressure fluid is adapted to be supplied to the jet pipe by an ordinary pump (not shown) through a stationary conduit 13 having a nozzle 14 projecting into the upper open end of the jet pipe. The jet pipe is adapted to deliver the fluid to one or the other or to both of a pair of orifices of the control 20 conduits 15 and 16 in a distributor block 17 to operate a control device (not shown), it being understood that the jet pipe moves relative to the orifices in response to changes in the condition to be controlled. In case liquid, such as oil, 25 is used, the jet pipe nozzle is surrounded by an oil catcher 18 which is usually kept full of oil returning through one or the other of the control conduits from the control device or by the oil not used or not delivered to one of the conduits.

30 From the above explanation of the illustrated example, it will be understood that the effective fluid pressure for actuating a control device has to be built up or regained in the respective control conduits 15 and 16 and the rate of flow, as well as the pressure therein are the important factors with which this invention is concerned. The ratio of the sizes of the nozzle and each orifice in terms of their diameters d/D , is less 35 than one to one. That is to say, the cross sectional area of the nozzle bore is less than that of the respective reception orifices, the areas of round nozzles and orifices being proportional to the squares of the diameters. For most suitable 40 fluids, a long series of experiments has demonstrated that best results are obtained when the ratio of the diameters ranges between one to two and one to one, depending upon some variable factors, such as the kind of oil used, the character of the jet, the distance between the nozzle and the receiving orifices and other factors.

45 Referring now to Fig. 3, there is shown an illustrative jet pipe nozzle 20 discharging into a conduit 21 having an orifice of larger diameter, 50

Having thus explained the nature of the invention, with the understanding that it is not limited to the illustrative embodiment thereof, what I claim and desire to secure by Letters Patent is:

5

1. Jet relay mechanism comprising, in combination, a reception orifice; and a nozzle movable relatively to said orifice and arranged to discharge a jet of pressure fluid into said orifice to build up a pressure in the same depending upon 10 the degree in which the nozzle and the orifice register, the cross sectional area of the nozzle bore being smaller than that of the orifice bore and greater than one fourth the cross sectional area of the orifice bore, whereby the loss of fluid 15 pressure and fluid volume becomes a minimum, and even a gain in pressure fluid volume may be attained.

2. Jet relay mechanism comprising, in combination, a reception orifice; and a nozzle movable 20 relatively to said orifice and arranged to discharge a jet of pressure fluid into said orifice to build up a pressure in the same depending upon the degree in which the nozzle and the orifice register, the cross sectional area of the 25 nozzle bore being approximately .64 of the cross sectional area of the orifice bore.

3. Jet relay mechanism comprising, in combination, a plurality of reception orifices; and a jet-pipe mounted for movement relatively thereto and arranged to discharge a jet of pressure fluid into said orifices to create a pressure in the same depending upon the degree in which the jet-pipe nozzle and the orifices register, the cross 30 sectional area of the jet-pipe nozzle being smaller than the bore of the orifices and greater than one fourth of the cross sectional area of the respective orifices.

4. Jet relay mechanism comprising, in combination, two reception orifices positioned adjacent to each other; and a jet-pipe pivotally mounted for movement relatively to said orifices and arranged to discharge a jet of pressure fluid into said orifices to create a pressure in the same depending upon the degree in which the jet-pipe nozzle and the orifices register; the cross sectional area of the jet-pipe nozzle being 40 smaller than the bore of the orifices and greater than one fourth of the cross sectional area of the orifices.

45

GUIDO WÜNSCH.

the ratio being represented by d/D . The straight arrows represent the fluid being delivered directly from the nozzle into the orifice and the curved arrows indicate fluid entering by the injector effect. However, some of the original fluid is usually dissipated by eddy currents, and the volumetric efficiency seldom exceeds 100% of the jet pipe delivery; but, in some cases, the volumetric efficiency is greater than 100%.

10 Fig. 4 is a graph or chart in which the curve is shown to illustrate the volumetric efficiency for a range of ratios of nozzle and orifice diameters between 1 to 2 or .5 and 1 to 1 or unity. This curve happens to represent the flow 15 efficiency of an oil which is an excellent example for illustrative purposes. It shows that the volumetric efficiency v/V for any ratio d/D between .5 and 1.0 is greater than the efficiency when the ratio is 1.0, the maximum efficiency 20 being obtained when the ratio is .8. Expressed in terms of the areas, this ratio would be .64 to 1 and the critical range of areas would be 1 to 4. Incidentally, V represents the volume delivered by the pump through the jet pipe and v the volume regained or delivered through the 25 conduit 21.

Fig. 5 is a graph or chart in which the curve is drawn to illustrate the pressure regain or efficiency under the same conditions as those explained in connection with Fig. 4. The curve also happens to show that the pressure regain or efficiency p/P for any ratio d/D between .5 and unity is greater than the efficiency when the ratio is unity. This curve very closely coincides 25 with the volumetric curve and also shows that a maximum pressure efficiency is obtained when the ratio d/D is approximately .8.

From the foregoing explanation of the charts, it will be seen that the ratio d/D should be within 40 the range .5 to 1 to produce the best results. An area ratio of approximately two to three or .64 to 1 (diameter about .8 to 1) has been chosen merely for illustration in Fig. 3. However, the critical ratio will be different depending upon the 45 characteristics of the operating fluid, the jet nozzle distance or clearance, fluid pressure and other variable factors. Satisfactory results have been obtained using regulator oils having viscosities from about 1000 to 20 Saybolt seconds, 50 with a pressure range of 20 to 130 pounds per square inch, and jet nozzle clearances up to about one-fourth of an inch. However, this is not intended to define any particular limits.
